UNITED STATES PATENT OFFICE.

EDWIN W. HAMMON, OF DAVISVILLE, CALIFORNIA.

DEVICE FOR CONVERTING MOTION.

SPECIFICATION forming part of Letters Patent No. 554,062, dated February 4, 1896.

Application filed September 13, 1895. Serial No. 562,430. (No model.)

To all whom it may concern:

Be it known that I, EDWIN W. HAMMON, a citizen of the United States, residing at Davisville, county of Yolo, State of California, have invented an Improvement in Devices for Converting Oscillatory into Continuous Rotary Motion; and I hereby declare the following to be a full, clear, and exact description of the same.

10 My invention relates to the general class of mechanisms or devices for converting motion from one form into another, and its object is to convert an oscillatory into a continuous rotary motion in the same direction.

15 It may be applied to any use to which it is adapted, and is especially useful in connection with the oscillatory motion of a vibratory engine, or such as are commonly known by the name of "sector-shaped" engines, 20 whereby their motion is conveniently and economically converted into a continuous rotary motion, and is adapted to be readily reversed.

25 My invention consists in the novel construction and arrangement of the parts of the device which I shall now fully describe.

Referring to the accompanying drawings, Figure 1 is a perspective view of my device. Fig. 2 is a horizontal section of same. Fig.

30 3 is an end view.

A is a shaft, to which an oscillatory motion may be supposed to be applied from any suitable source, unnecessary herein to show. Firmly secured upon the shaft is a large gear 35 B having a bevel-face with teeth.

C is a shaft mounted horizontally and parallel with the plane of rotation of the gear B. Loosely mounted upon the shaft C, one at each end thereof, are bevel-pinions D, each 40 of which meshes at opposite sides with the gear B.

E are crank-arms, fast upon the shaft C.

F is a slide-rod, the ends of which slide within the extremities of the arms E and are 45 adapted to enter sockets d in the bevel-pinions D.

Upon shaft C is a freely-slidable flange c, guided by suitable means in its movement so that it will not cramp, said means being here 50 shown as the pins c' and brackets c'.

The slide-rod F passes freely through this flange. Springs G encircle the slide-rod F

and lie between the flange c and suitable stops in the shape of buffers f upon the ends of said slide-rod.

55 H is a rod extending in front of gear B and in the diametrical plane thereof. It carries a clutch-shifter h in the shape of separated or spaced plates, which are adapted to engage the periphery or rim of the flange c. The extremities of rod H pass backwardly behind gear B and are pivoted at h' to a bearing I, so that said rod may move laterally over the face of gear B. Upon the face of said gear are stops b adapted to come in contact with rod 60 H from opposite sides.

The bearing I, to which the ends of the rod H are secured, is a rocking one, pivoted upon a center at i, whereby, by its movement through the operation of a suitable lever, such as J, the upper portion of said rod may be thrown sufficiently close to the face of the gear B to cause the stops b to come in contact with it, while the lower portion is by the same movement thrown far enough away from the 75 face of the gear B to allow the stops to pass by it without contact. A reverse movement of the rocking bearing I causes the lower portion of the rod to be thrown into the path of the stops, while the upper portion is thrown 80 out of said path.

70 The operation of the device is as follows: When the rocking bearing I is so turned that the upper portion of rod H is in the path of movement of the stops b, the gear B on being 85 oscillated in one direction will cause one of said stops, by contact with the rod H, to force the whole rod over to one side, and said movement of the rod, through its clutch-shifter h engaging the freely-sliding flange c, will cause 90 the latter to move over to the same side, thereby condensing or compressing the spring G on that side, which, bearing on the buffer-stop f, will cause the slide-rod to move over in that direction, so that its extremity will enter 95 the socket d in the pinion D on that side. Now, as said slide-rod is engaged with the pinion and is also engaged with the crank-arm E of the shaft C, the return movement of the gear B will cause through the engaged pinion a 100 movement of the shaft C in a given direction, while the other pinion is moving freely upon said shaft in a reverse direction. This continues until the other stop b of the gear B

comes up into contact with the rod H from the other side, and thereby moves said rod back again, and this movement, through the clutch-shifter h, will slide the flange c over to 5 the other side, causing it to compress the spring G on that other side, and thereby, as soon as the socket d in the other pinion comes 10 opposite to the slide-rod, the end of said slide-rod will thereupon spring into said socket 15 and thus become engaged with the other pinion, and this movement will free it of the first pinion. Thereupon the gear B, returning in the first direction, will cause, through the now engaged second pinion, a movement of the 20 shaft C in the same direction in which it moved in the first instance, thereby continuing in the same direction the rotary motion of said shaft. This will continue until the first stop b again engages the rod H and moves 25 said rod over again for a repetition of the first operation.

In order to reverse the movement it is only necessary to rock the bearing I, so that the lower portion of the rod H will be brought 25 into action, the upper portion being thereby thrown out of action.

The stop K on the back of gear B, Figs. 2 and 3, by coming in contact with fixed stops L, positively limits the oscillation of said gear, 30 and thus effects the accurate operation of the device independently of what may be a slightly-variable stroke of the engine. This is especially of advantage where the oscillatory movement is derived from such an engine as a sector-shaped engine, where the 35 oscillating piston is limited by cushioning on steam, and, therefore, may not have a stroke sufficiently accurate for the requirements of the converting mechanism. This necessity 40 for accuracy follows into the construction of the device with regard to the proportions and time of the engaging gear B and pinions D, these being such that the alignment of the sockets d in the two pinions must take place 45 at the limits of the stroke or oscillation of the gear B. To take place prior to this time would result in reversing the motion.

Having thus described my invention, what I claim as new, and desire to secure by Letters 50 Patent, is—

1. Means for converting oscillatory into continuous rotary motion, consisting of a driving-gear to which the oscillatory motion is initially imparted, independent pinions meshing 55 at opposite sides of said gear and at right angles therewith, a driven shaft upon which said pinions are loosely mounted, and a means comprising a slide-rod having its extremities adapted to alternately engage the pinions and 60 appliances operated by the oscillation of the gear, for alternately engaging and disengaging said pinions from the pinion-shaft.

2. Means for converting oscillatory into continuous rotary motion, consisting of a driving-gear to which the oscillatory motion is imparted, independent pinions meshing at opposite sides of said gear and at right angles 65

therewith, a driven shaft upon which said pinions are loosely mounted, and a means operated by the oscillation of the gear for alternately engaging and disengaging said pinions from the shaft, consisting of crank-arms on the driven shaft, a slide-rod mounted between said crank-arms and having its extremities adapted to alternately engage sockets in the pinions, and devices on the oscillating driving-gear for alternately operating said slide-rod. 70 75

3. Means for converting oscillatory into continuous rotary motion, consisting of a gear to which the oscillatory motion is imparted, independent pinions meshing at opposite sides of said gear and at right angles therewith, a shaft upon which said pinions are loosely mounted, and a means, operated by the oscillation of the gear, for alternately engaging and disengaging said pinions from the shaft, consisting of crank-arms on the shaft, a slide-rod mounted between said crank-arms and having its extremities adapted to alternately engage 80 85 sockets in the pinion, and devices on the main gear for alternately operating said slide-rod, comprising a movable clutch-shifter on the face of the gear, stops on the gear for alternately moving said clutch-shifter in opposite directions, a slide-flange on the shaft with which the clutch-shifter engages and 90 springs on the slide-rod adapted to be alternately operated by the flange to project the slide-rod into its engagement with the pinions. 95 100

4. Means for converting oscillatory into continuous rotary motion, comprising a gear to which the oscillatory motion is imparted, pinions meshing with opposite sides of said gear and at right angles therewith, a shaft upon 105 which said pinions are mounted loosely, crank-arms fixed on the shaft, a spring-controlled slide-rod mounted in said arms and adapted to engage sockets in the pinions, a slidable flange for alternately operating the springs to 110 actuate the slide-rod alternately, a rod mounted in the diametrical plane of the face of the shaft B and pivoted so as to be moved from side to side, a clutch-shifter on said rod for engaging the sliding flange, and oppositely-located stops on the gear for alternately moving 115 the rod. 120

5. Means for converting oscillatory into continuous rotary motion, comprising a gear to which the oscillatory motion is imparted, pinions meshing with opposite sides of said gear and at right angles therewith, a shaft upon 125 which said pinions are mounted loosely, crank-arms fixed on the shaft, a spring-controlled slide-rod mounted in said arms and adapted to engage sockets in the pinions, a slidable flange for alternately operating the springs to actuate the slide-rod alternately, a rod mounted in the diametrical plane of the face of the shaft B and pivoted so as to be moved from side to side, a clutch-shifter on said rod for engaging the sliding flange, oppositely-located stops on the gear for moving the rod alternately, and a rocking bearing to which the 130 135

ends of the rod are secured whereby its upper portion and its lower portion may be thrown alternately into or out of engagement with the stops, whereby the motion transmitted 5 may be reversed as desired.

6. Means for converting oscillatory into continuous rotary motion, consisting of a gear to which the oscillatory motion is imparted, independent pinions meshing at opposite sides 10 of said gear and at right angles therewith, a shaft upon which said pinions are loosely mounted, crank-arms on said shaft, a slide-

rod mounted between said crank-arms and having its extremities adapted to alternately engage sockets in the pinions, devices on the 15 gear for alternately operating said slide-rod, and stops for accurately and positively limiting the stroke or oscillation of said gear.

In witness whereof I have hereunto set my hand.

EDWIN W. HAMMON.
